US00D577672S

(12) **United States Design Patent**
Yao

(10) **Patent No.:** **US D577,672 S**
(45) **Date of Patent:** **** Sep. 30, 2008**

(54) **LEAD CONNECTOR**

(76) Inventor: **Yi Hui Yao**, No. 18, Ke Ji East Road, High & New Technology Development Zone, Huanghe Road, Shantou, Guangdong (CN)

(**) Term: **14 Years**

(21) Appl. No.: **29/273,947**

(22) Filed: **Mar. 19, 2007**

(51) **LOC (8) Cl.** **13-03**

(52) **U.S. Cl.** **D13/133; D13/149**

(58) **Field of Classification Search** **D13/133, D13/149, 151, 153, 154, 184, 199; 439/260, 439/329, 409, 412, 417, 441, 492, 495, 570, 439/709, 715, 716, 717, 721, 729, 835; 361/119, 361/823**

See application file for complete search history.

(57) **CLAIM**

The ornamental design of the lead connector, as shown and described.

DESCRIPTION

FIG. 1 is a bottom plan view of a lead connector showing my new design;

FIG. 2 is an elevational view of the right side of the lead connector of the present invention;

FIG. 3 is an elevational view of the front side of the lead connector of the present invention;

FIG. 4 is an elevational view of the left side of the lead connector of the present invention;

FIG. 5 is a top plan view of a lead connector of the present invention;

FIG. 6 is an elevational view of the rear side of the lead connector of the present invention;

FIG. 7 is a perspective view of the lead connector of the present invention;

FIG. 8 is an exploded view of the lead connector of the present invention; and,

FIG. 9 is a perspective view of the lead connector of the present invention in use.

The broken line showing in the figure drawings is included for illustrative purposes only and forms no part of the claimed design.
